SAND RECONDITIONING AND RETEMPER-
ING APPARATUS

Edward H. Whittaker, Jersey City, N. J.

Original application July 9, 1941, Serial No.
401,651. Divided and this application October
24, 1942, Serial No. 463,231

9 Claims. (Cl. 22—89)

This invention relates to sand reconditioning and retempering apparatus which may be used in foundry plants, and this application is a division of an application for United States patent on Foundry plants, filed by me on July 9, 1941, Serial Number 401,651.

The principal object of the invention is to provide a simplified sand reconditioning and retempering apparatus, employing a spray and an excess water drainage system, with the efficient removal of trash and the like from the sand.

Another object is to provide a sand reconditioning and retempering apparatus wherein the sand is freed of trash, and the excess water drainage system and trash removal system are independent, so that the trash will not clog the excess water drainage system.

Still another object is to provide an apparatus as above described, whereby the sand is retempered evenly.

Another object is to provide an apparatus for reconditioning and retempering sand, wherein portions of the mechanism have dual functions, and the number of parts of the mechanism are relatively few, simple, not apt to get out of order and quite easy to replace.

Other objects and advantages of the invention will appear in the following detailed description, taken in connection with the accompanying drawing, forming a part of this specification, and in which drawing:

Figure 1 is a vertical longitudinal sectional view of the mechanism of the sand reconditioning and retempering apparatus, as well as a shake-out station and a conveyor, parts of the latter being in elevation.

Figure 2 is a fragmentary transverse sectional view through a portion of a pulverizing and trash separation chamber and a drainage and conveying chamber of the sand reconditioning and retempering apparatus.

The apparatus preferably includes a bottomless main body portion or frame 10 open at its upper end to provide an inlet and provided with end walls 11 and 12 and like side walls 13, defining, generally, from the upper end downwardly, spray chamber 14, an intermediate or pulverizing and trash separation chamber 15, a lower or drainage and conveying chamber 16 and a filtering chamber 17 to one side of the chamber 16. There may be provided also a spout or way 18 for the reconditioned and retempered sand, and an inclined water trough 19.

Into the spray chamber 15 extend one or more spray pipes or conduits 20, perforated as at 21

through which water may be sprayed upon material falling from above. The spray pipe 20 may extend through a slot or peep-hole 22 in the wall 11 and be free of the wall 12, at its closed end 23, thus being movable so that a workman located outside the frame 10, as in the zone 24, may move the pipe 20 about in the spray chamber 14. With this end in view, the pipe 20 is supplied with water through a flexible hose 25 having connection with a manually operable valve 26 in a pipe line 27 beneath the conveying chamber 16 and extending into a zone 28 outside the frame 10, where another workman may be located to control the valve 26. In this pipe line 27 is another valve 29 which may be used to regulate the maximum flow of water that may be delivered to valve 26. The control 30 of valve 29 may be provided with a lock or seal 31 to prevent tampering. The valve 26 may be controlled by a foot lever 32, pivoted at 33, intermediate its ends, to the wall 12 of the frame 10, with treadle portion 34 projecting at one end outside the wall 12 and connected at its other end, inside the frame 10, with a line 35 which is operatively connected with the lever handle 36 of the valve 26. A weight 37 may be provided adjacent the lever end of link 35 to normally close valve 26.

Next, with reference to the drainage and conveying chamber 16, this is defined at its bottom by an inclined trough portion 40 semi-circular in cross-section as shown in Figure 2, which trough portion 40 extends upwardly from the filtering chamber 17 to the upper end of spout 18. In the chamber 16, cooperating with the trough portion 40 is a screw conveyor 41, the shaft 42 of which is journaled in bearings 43 carried by the walls 11 and 12 of 10. The purpose of this conveyor is to allow excess water to drain from the sand and flow to the filtering chamber 17 while the moist sand is more or less slowly raised and dumped into spout 18. The shaft 42 may be slowly rotated by motor 44, through speed reduction gearing 45, located in the zone 24.

In the pulverizing and trash separation chamber 15 is disposed a vibrating grille 50 through the openings or perforations 51 of which sand and water may flow, while trash, such as nails, wooden wedges, binding wire, cores which have freed themselves from the casings, small pieces of broken castings, etc., will find egress from the chamber 15 through opening or outlet 52 in the wall of chamber 15, shown in Figure 2, normally closed by a yielding apron or gate 53 suspended

from above so as to normally close the opening, as shown. The grille is preferably pivoted to swing about a horizontal axis, as at 54, adjacent the lower part of opening 52 and may be vibrated by means associated with the screw conveyor 41. This means is shown as including cams or eccentrics 55 on shaft 42 and upwardly extending, reciprocating rods or members 56 supported loosely by guides 57 carried by the walls 11 and 12, having operative engagement with the cams 55 at their lower ends, and fitting loosely in sockets 58 open to the under side of grille 50. The throws of cams 55 are such that the grille 50 always inclines upwardly from its pivotal axis 54, so that trash and the like, too large to go through the perforations 51, will gravitate to the apron or gate 53 and, when there is a sufficient accumulation to overcome the inherent tendency at the gate 53 to remain closed, will quickly find exit, when the gate opens, sliding through the opening 52, due to gravity. In order to prevent trash from finding its way to the drainage and conveying chamber 16, the free longitudinal edge 59 of the grille 50 may rub against a flexible wall portion 60 of chamber 15 as shown in Figure 2, this flexible wall portion 60 being disposed of across suitable opening 60' in the wall and the main body portion, and is opposite the opening 52. Trash finds an exit at opening 52 and falls into a container 61, supported on a shelf 62, which, in turn, is supported laterally of frame 10.

In the filtering chamber 17 is disposed a reticulate box or lining 63 containing filtering material 64, such as gravel, to catch any water borne sand, while the water may flow through the openings in the box 63 and through the outlet or opening 65 to the trough 19 and be carried away, either for re-use or as waste.

Associated with this novel sand reconditioning and retempering apparatus, are a shake-out station 70 above and a conveyor 71 below the sand reconditioning and retempering apparatus.

The shake-out station may include a grille 72 adapted to support a flask and mold, vibrating or shaking mechanism 73 below the grille 72, both the grille 72 and the vibrating mechanism 73 being so disposed that the sand or trash will fall into the sand reconditioning and tempering apparatus.

The conveyor 71 may be of the endless type and include a portion 75 passing through a housing 76 including the floor 77, upon which the sand reconditioning and tempering apparatus rests. An opening 78 in the floor 76 communicates between the housing 76 and the spout 18, so that the tempered sand will drop through the opening 78 and into the housing 76 and be conveyed to the next station by the conveyor 71.

As the sand, broken castings, trash and the like are shaken from the flask at the shake-out station, they will drop into the open-topped sand reconditioning and retempering apparatus, enter the spray chamber 15, encounter the spray played about by the workman, the sand being whetted and the sand, trash and the like deposited upon the grille 50, whereupon the sand and water will drop through the perforations 51 in the grille 50, while trash will move toward the opening 52, as has been explained, and be discharged from the apparatus as it accumulates. The slow upward travel of the wet sand, urged and turned over and over by the conveyor 41, will free it of excess water and discharge it, as properly retempered sand, into the spout 18.

The manually movable spray means enables

the workman to play the water where needed and the incidental jarring of the spray pipe 20 prevents the accumulation of sand and fine trash thereon, which accumulation would tend to clog the perforations 21.

Rotation of the conveyor shaft 42 also operates the grille 50 by swinging the latter back and forth about its pivoted axis.

The construction is such that fumes will not accumulate in the apparatus, nor will it become flooded and there are no gears or delicate working parts to be damaged by the trash and sand.

I claim:

1. In apparatus for reconditioning sand, a main body portion providing an upper chamber, an intermediate chamber having a lateral opening in said main body portion, and a lower chamber beneath said intermediate chamber, water spray means in said upper chamber, a grille pivoted to said main body portion adjacent said opening, extending across said intermediate chamber and movable in planes inclined downwardly toward said opening, including a gate across said opening, suspended from adjacent the upper end of said opening and forming, with said grille, an acute angle, movable means in said lower chamber for receiving sand and spray water, dropped through said grille, and means, operated by movement of said last named means, for swinging said grille about its pivotal axis.

2. Apparatus for tempering sand, comprising a main body portion providing an upper spray chamber, a pulverizing and trash separation chamber therebeneath and a drainage and conveying chamber beneath said last mentioned chamber, said spray chamber having movable spray means therein, said pulverizing and trash separation chamber provided with a lateral opening and a grille pivoted adjacent the lower portion of said opening, extending across the chamber and movable in a plane inclining downwardly toward said opening, a conveyor in said drainage and conveying chamber, said conveyor disposed in a plane inclining from one side of the main body portion upwardly toward the other side thereof, means for operating said conveyor, means operable by said conveyor for swinging said grille about its pivotal axis, and a yieldable apron or gate at the lower margin of said grille for normally closing said lateral opening.

3. In apparatus for tempering sand, a main body portion providing an upper chamber, an intermediate chamber having a lateral opening through said main body portion, and a lower chamber beneath said intermediate chamber, spray means in said upper chamber, a grille pivoted adjacent the lower portion of said opening, extending across said intermediate chamber and movable in a plane inclined downwardly toward said opening, a rotating conveyor in said lower chamber, disposed in the path of materials dropped from said grille, means for operating said conveyor, means operable by said conveyor for swinging said grille about its pivotal axis and gate means at the lower margin of said grille for normally closing said opening.

4. In apparatus for tempering sand, a main body portion providing an upper chamber, an intermediate chamber having a lateral opening through said main body portion, and a lower chamber beneath said intermediate chamber, spray means in said upper chamber, a grille pivoted adjacent the lower portion of said opening, extending across said intermediate chamber and movable in

a plane inclined downwardly toward said opening, a rotating conveyor in said lower chamber, disposed in the path of materials dropped from said grille, means for operating said conveyor, means operable by said conveyor for swinging said grille about its pivotal axis including a cam rotatable with said conveyor and a rod with one end riding upon said cam and with its other end in contact with the under side of said grille, and gate means at the lower margin of said grille for normally closing said opening.

5. In apparatus for tempering sand, a main body portion providing an upper chamber, an intermediate chamber having a lateral opening through said main body portion, and a lower chamber beneath said intermediate chamber, spray means in said upper chamber, a grille pivoted adjacent the lower portion of said opening, extending across said intermediate chamber and movable in a plane inclined downwardly toward said opening, a conveyor having a shaft portion in said lower chamber, disposed in the path of materials dropped from said grille, means for operating said conveyor, means operable by said conveyor for swinging said grille about its pivotal axis, including a cam mounted upon said shaft portion and a reciprocating rod with its lower end riding upon the surface of said cam and its upper end in contact with the under side of said grille at a location remote from the pivot of said grille, and gate means at the lower margin of said grille for normally closing said opening.

6. In sand tempering and retempering apparatus, a main body portion providing an upper chamber, an intermediate chamber, having an outlet to the exterior of said main body portion, a lower chamber beneath said intermediate chamber and a filtering chamber at one side of said lower chamber, provided with an outlet to the exterior of said main body portion, spray means in said upper chamber, a movable grille across said intermediate chamber, sloping downwardly toward said outlet, a trough in said lower chamber, extending from said filtering chamber upwardly towards said intermediate chamber and disposed beneath said grille, a screw conveyor in said trough and means to rotate said conveyor to urge material therein upwardly in said trough.

7. In sand tempering and retempering apparatus, a main body portion providing an upper chamber, an intermediate chamber, having an outlet to the exterior of said main body portion, a

lower chamber beneath said intermediate chamber and a filtering chamber at one side of said lower chamber, provided with an outlet to the exterior of said main body portion, spray means in said upper chamber, a movable grille across said intermediate chamber, sloping downwardly toward said outlet, a trough in said lower chamber, extending from said filtering chamber upwardly towards said intermediate chamber and disposed beneath said grille, a screw conveyor in said trough, means to rotate said conveyor to urge material therein upwardly in said trough, and means operable by said conveyor for moving said grille into various planes inclining downwardly toward said opening.

8. In sand conditioning apparatus a main body portion provided with a sand and trash inlet, a trash separation chamber below said inlet, and a conveying chamber beneath said first-named chamber, said first-named chamber having a lateral outlet to the exterior of said main body portion, a grille pivoted adjacent the lower end of said outlet, extending across said first-named chamber and movable in planes inclined downwardly toward said outlet, a yieldable apron or gate normally closing said outlet and suspended from the wall above said outlet, a rotatable conveyor in said second-named chamber, means for rotating said conveyor, and means operable by said conveyor for swinging said grille about its pivotal axis.

9. In sand conditioning apparatus a main body portion provided with a sand and trash inlet, a trash separation chamber below said inlet, and a conveying chamber beneath said first-named chamber, said first-named chamber having a lateral outlet to the exterior of said main body portion and a flexible wall portion carried by said main body portion in the wall thereof opposite said lateral outlet, a grille pivoted adjacent the lower end of said outlet, extending across said first-named chamber and movable in planes inclined downwardly toward said outlet, and movable over the surface of said flexible wall portion, a yieldable apron or gate normally closing said outlet and suspended from the wall above said outlet, a rotatable conveyor in said second-named chamber, means for rotating said conveyor, and means operable by said conveyor for swinging said grille about its pivotal axis.

EDWARD H. WHITTAKER.
